FLYING MACHINE

Walter Charles Pitter, Epping, England

Application February 8, 1933, Serial No. 655,831
In Great Britain February 15, 1932

21 Claims. (Cl. 244—11)

This invention relates to flying machines and to apparatus for the propulsion of fluids, and has for its object to provide a new blade or plane action for such machines, or apparatus.

8 The present invention comprises wing flapping apparatus for use in flying machines or for the propulsion of fluids, comprising two or more pairs of radially arranged wings connected by transversely arranged hinges at their inner 10 ends to a tubular member rotatable about a fixed shaft but not movable axially thereon, means being provided whereby the wings can be rocked or oscillated about their hinges.

It is well known, as set forth in British Patent 15 No. 7745 of 1909, that by moving a propeller along its axis the resistance of the air to such movement will cause the blades to rotate about their axis if free to do so, and that when such a device is fixed vertically as in an auto-gyro 20 or windmill aeroplane it will enable the machine to descend almost vertically, and when propelled in the usual manner to rise at a much steeper angle than is possible with an ordinary flying machine. In the present invention a modification 25 of such a device is used as a supporting plane in a flying machine. In such modification use is made of radially arranged wings freely rotatable as heretofore about a vertical axis, the wings however being so constructed that they 30 will be transversely flexible or movable each about its own longitudinal axis within limits and such as set forth in my prior specification.

In the present invention the radial wings are flapped or oscillated to and from the vertical 35 axis of the device about hinges or pivots which are carried by a non-axially movable but freely rotatable sleeve.

By arranging the wings in or near the same plane and operating them in such a manner 40 that while some of them are oscillating or moving angularly upwards others will be oscillating downwards, the descending wings will meet an upward supporting current or flow of air caused by the wings oscillating upwards.

45 The ascending pair of wings, owing to the downward flow of air made by the descending pair of wings, are driven forward with greater force and thereby turn the descending pair of wings at a greater speed against a greater resistance, thereby adding to the support of the machine as a whole. This upward stroke is of the greatest importance, as it is from this that most of the forward and rotative effort is obtained, and, under some circumstances all the 50 forward pull and rotative effort is obtained by

the ascending wings to pull the descending planes or wings forward, against the upward flow made by the ascending pair of wings, and as the angle is different and is such that in descending they are at an angle of incidence to the downward 60 and rotary velocity, and being pulled forward at this angle, help to lift the machine as a whole.

The angle of incidence of the wings constructed as herein set forth, when on the upward stroke 65 will always be different from the angle of the same wings when on the downward stroke, as it is necessary to get the main rotative effect on the upward stroke and in some cases (as when rising rapidly) to get all the rotative effect from this upward stroke, the downward stroke being mostly used to support and raise the machine (not by beating on the air), but by planing on the downward stroke at an angle to the horizontal. 70

This angle will be determined by circumstances, 75 such as with a heavy load the machine will rise slowly, the angle to the forward and downward resultant being greater, but with a light load the rise will be quicker, due to the angle of descending wing being less to the forward and 80 downward resultant.

On the upward stroke and according to the speed of it, the wings will take a greater angle and dart forward and upwards, the pair of wings on the downward stroke will take an angle according to the weight of the machine and the adjustment of springs determining the angle of incidence, and will plane forward owing to the pull of the ascending wings, and being at an angle of incidence to the forward and downward resultant, will lift the machine. 85

It must be understood that great advantages are obtained by flapping or oscillating wings that are hinged at one end, as against planes that are merely reciprocated all along their length at the same speed, so that the outer end or tip of wing passes a greater distance through the air. The mechanical difficulties of getting sufficient reciprocating movement on planes to reciprocate them a sufficient distance to change their angle 95 of incidence from the up to the down stroke, and yet leave sufficient movement for the driving and supporting effect being very great, and by flapping, as a bird flaps its wings, all advantages are obtained without the disadvantages. 100

Any suitable number of such sets of planes or wings may be provided on one vertical shaft.

The blades or wings have preferably rigid front edges and flexible rear edges or may be rigid blades or planes set in sockets and spring-con- 110

trolled and allowed to tilt or oscillate within predetermined limits, and are set on the shafts at an angle of incidence to the horizontal and are moved about their hinges by connecting rods or other suitable means operated by any suitable motive power so as to produce a reciprocating motion so that the resultant action of the wings on the air will produce a rotary motion in the sleeve.

10 The upward velocity of the whole machine will be determined by the resultant angle of incidence of the wings or blades due to their upward stroke and to the flexibility of the blades or wings and is supported by the pressure on the surrounding air by the blades or wings on the downward stroke.

15

Means such as stops may be arranged to prevent the blades or wings flexing more than is necessary or desirable for their purpose.

20 In the accompanying drawings various features
of the invention are illustrated, Figure 1 being a
general sectional elevation of the apparatus,
Fig. 1a is an elevation view of an adaptation of
the device. Figure 2 a plan on an enlarged scale
25 of one method of hinging the wings at their inner
ends to the rotary tubular member, Figure 3 is a
detail of a socket connecting the wing to the hinge
member, and Figure 4 a sectional detail of the
same, Figure 5 is an alternative construction of
30 the wing socket connection, Figure 6 illustrates
a modified method of rocking the wings about
their hinges or pivots, and Figure 7 is a sectional
plan of Figure 6.

35 In these drawings *a* is a fixed shaft, *b* a tubular member or sleeve rotatable thereon but prevented from axial movement thereon by collars *e*, *e*1, each end of the tubular member or sleeve *b* being provided with a ball bearing *c* and a thrust bearing *d*.

40 Hinged to the sleeve *b* and by hinges or pivots *g*₁, *g*₂, *g*₃ and *g*₄ are four wings *f*₁, *f*₂, *f*₃ and *f*₄, carried by supporting arms *r*₁, *r*₂, *r*₃ and *r*₄, the hinges being at the inner ends of the wings with their axes arranged transversely to the axis of
 45 the shaft *a*.

Pivoted to each of the wings at a suitable distance from the hinges g_1 , are connecting rods h_1 , h_2 , h_3 and h_4 one end of each rod being connected by a pivot p , to its respective wing the other end of each rod being connected by a pivot i_1 to a sleeve i adapted to slide on the sleeve b but prevented from rotation thereon by a feather k and keyway k_1 . It will thus be seen that a flapping or oscillating motion of the wings f_1 to f_4 to and from the shaft a can be obtained by reciprocating the sleeve i , and by extending any of the supporting arms r_1 to r_4 beyond their pivots or hinges g_1 to g_4 and connecting the corresponding rods to such extensions the corresponding wings will be oscillated in the opposite direction to the others. In the example shown (see Figure 2) the wing supporting arm r_2 is extended to p_2 and the wing supporting arm r_4 to p_4 , so that the wings will move in pairs in opposite directions. To facilitate this movement where the two arms r_3 and r_4 cross each other they are formed with overlapping bends x .

The sleeve *i* can be reciprocated by any suitable power and this may be effected in the manner illustrated by applying the power to a sleeve *l* adapted to be reciprocated on the shaft *a*, by any suitable power this shaft is supported in any suitable manner according to the use of the device such as in the case of a flying machine by being connected to the fuselage of the machine.

The apparatus for reciprocating the sleeve *l* may be provided with any suitable means for varying its stroke.

In the example illustrated the sleeve l is connected by links m , m to a ring j mounted on a thrust bearing $j1$ carried by the sleeve i , the ends of the links m , m being pivoted to the ring j and sleeve l respectively.

To facilitate the assembly of the parts of the device the tubular member b may be divided longitudinally into two parts by a coupling b_1 carrying a ball bearing e_1 .

The inner ends of the arms $r1$ to $r4$ may be supported in sockets s (see Figure 3) carrying the hinges $g1$ to $g4$ and in order that the wings connected to the arms $r1$ to $r4$ can each partake of a certain amount of angular movement on the axis of its arm, such arm r is rotatably mounted in the socket s , the limit of such movement being determined by stops $r7$ fixed in a collar $r5$ fixed on the arm $r1$ and moving in transverse slots $r8$ formed in the socket $s3$, and in order that such rotary or angular movement shall be resilient and the wing restorable to its normal position, the arm $r1$ is connected by a collar $r5$ fixed thereon to one end of a tension spring $r6$ the other end of the spring being fixed to the end of the socket s . In order to prevent the wings from moving radially by centrifugal force out of the sockets s , pins $s1$ are driven through the shaft $r1$ and extend into transverse slots $s2$ provided in the socket s . To limit the action of this spring $r6$ two pins $r7$ extend from the collar $r5$ into slots $r8$ formed in an outer socket $s3$ fixed on the socket s .

In the base of the socket s is provided a torsion or spiral spring $r9$ one end of which is fixed to the rod $r1$ and the other to the socket s , the springs $r6$ and $r9$ being oppositely biased so that the wing can be set at the desired angle of incidence, and so that the spring action will tend to return the blade to such angle when the apparatus is inoperative. 110 115

In the modification shown in Figures 6 and 7 one pair of wing arms r_1, r_3 are arranged to cross each other in the same plane, thus r_3 is forked at its inner end so that the inner end of r_1 can pass through it about the pivot g , the inner end of the rod h_1 being connected through a forked opening in the end of r_3 by its pin p_1 , while the end of the rod h_3 is forked and connected to the outside of the forked end of r_3 by its pin p_3 . In this construction the second pair of wing arms are arranged a sufficient distance such as at g below or above the other pair so that they will be clear of each other.

The wings or blades are shown more fully in Figure 5 in which the socket portion is as described above with reference to Figures 3 and 4, the spring $r6$ being substituted by inclined radially arranged springs $r10$, of which the inner ends are fixed to a sleeve $s3$ mounted on the socket s while their outer ends are fixed to the outer ends of radial arms $r11$ fixed on the wing member $r1$.

In the case of a flying machine the main shaft 140 may be kept vertical by means of gyroscopic apparatus driven by any suitable motor on the machine.

In some cases in order to cause the machine to glide in the desired direction means are provided whereby the position of the centre of gravity of the machine with respect to the vertical shaft can be changed in the direction in which it is desired to effect the gliding. 145

When the blade flapping apparatus is used on 150

a flying machine, in order to maintain the vertical shaft in an upright position notwithstanding changes in position of the centre of gravity of the machine, gyroscopic apparatus is provided on the vertical shaft, as indicated at G on Figure 1a, and in order to provide means for enabling the machine to glide in any particular direction by changing the position of the centre of gravity, the vertical shaft is mounted in a platform F mounted on runners sliding on a frame B1 which by means of bearings B2 slides in a transverse direction on runners B3 fixed in the fuselage F1. The relative moves of these parts is effected by means of lever mechanism L provided with ball and socket members L1 and L2 whereby when the lever is moved in one direction alters the position of the centre of gravity and when moved transversely alters the position of the centre of gravity correspondingly, and so that the movement of the lever in an angular direction effects a corresponding resultant movement of the position of the centre of gravity of the machine with reference to the fixed vertical shaft.

What I claim and desire to secure by Letters Patent is:—

1. Blade flapping apparatus for use in flying machines and for the propulsion of fluids, comprising a multiplicity of pairs of radially arranged blades, a corresponding number of blade carrying rods, a corresponding number of springs, a sleeve and a fixed shaft, the sleeve being rotatively mounted on the fixed shaft, means for preventing axial movement of the sleeve on the shaft, and the blades set at an angle of incidence to their direction of rotation, on the blade carrying rods by means of the springs, the inner ends of the blade carrying rods hinged at their inner ends to the sleeve, and means whereby they can be oscillated to and from the axis of the sleeve.

2. Blade flapping apparatus for use in flying machines comprising a multiplicity of pairs of radially arranged blades, a sleeve and a fixed vertical shaft, the sleeve being rotatively mounted on the fixed vertical shaft, means for preventing axial movement of the sleeve on the shaft thereon and the blades set at an angle of incidence to their direction of rotation and hinged at their inner ends to the sleeve, and means whereby they can be oscillated to and from the axis of the sleeve, means for varying position of the centre of gravity of the machine from the fixed vertical shaft when gliding, the variations of the position of the centre of gravity being along the direction of gliding desired.

3. Blade flapping apparatus for use in flying machines and for the propulsion of fluids, comprising a multiplicity of pairs of radially arranged blades, a corresponding number of blade carrying rods, a corresponding number of springs, a sleeve and a fixed shaft, the sleeve being rotatively mounted on the fixed shaft, means for preventing axial movement of the sleeve on the shaft, and the blades set at an angle of incidence to their direction of rotation, on the blade carrying rods by means of the springs, means for limiting the angular movement of the wing on its supporting rod, the inner ends of the blade carrying rods hinged at their inner ends to the sleeve, and means whereby they can be oscillated to and from the axis of the sleeve.

4. Blade flapping apparatus for use in flying machines and for the propulsion of fluids, comprising multiplicity of pairs of radially arranged blades, a corresponding number of blade carrying

rods, a corresponding number of pairs of torsion springs, a sleeve and a fixed shaft, the sleeve being rotatively mounted on the fixed shaft, means for preventing axial movement of the sleeve on the shaft, and the blades set at an angle of incidence to their direction of rotation, on the blade carrying rods by means of a pair of the torsion springs oppositely disposed, the inner ends of the blade carrying rods hinged at their inner ends to the sleeve, and means whereby they can be oscillated to and from the axis of the sleeve.

5. Blade flapping apparatus for use in flying machines comprising a multiplicity of pairs of radially arranged blades, a sleeve and a fixed vertical shaft, gyroscopic apparatus, the sleeve being rotatively mounted on the fixed vertical shaft, means for preventing axial movement of the sleeve on the shaft thereon, and the blades set at an angle of incidence to their direction of rotation and hinged at their inner ends to the sleeve, and means whereby they can be oscillated to and from the axis of the sleeve, the gyroscopic apparatus being fixed with reference to the fixed vertical shaft to maintain it in the vertical position.

6. Blade flapping apparatus for use in flying machines and for the propulsion of fluids, comprising a multiplicity of pairs of radially arranged blades, a corresponding number of blade carrying rods, a corresponding number of sockets carrying the blade carrying rods at their inner ends, a corresponding number of springs, a sleeve and a fixed shaft, the sleeve being rotatively mounted on the fixed shaft, means for preventing axial movement of the sleeve on the shaft, and the blades set at an angle of incidence to their direction of rotation, on the blade carrying rods by means of springs, the inner ends of the sockets carrying blade carrying rods hinged at their inner ends to the sleeve, and means whereby they can be oscillated to and from the axis of the sleeve.

7. Blade flapping apparatus for use in flying machines and for the propulsion of fluids, comprising a multiplicity of pairs of radially arranged blades, a corresponding number of blade carrying rods, a corresponding number of sockets carrying the blade carrying rods at their inner ends, means for preventing the blade carrying rods from moving out of their sockets by centrifugal force while allowing angular movement of them in the sockets, a corresponding number of springs, a sleeve and a fixed shaft, the sleeve being rotatively mounted on the fixed shaft, means for preventing axial movement of the sleeve on the shaft, and the blades set at an angle of incidence to their direction of rotation, on the blade carrying rods by means of the springs, the inner ends of the sockets carrying blade carrying rods hinged at their inner ends to the sleeve, and means whereby they can be oscillated to and from the axis of the sleeve.

8. Blade flapping apparatus for use in flying machines and for the propulsion of fluids, comprising a multiplicity of pairs of radially arranged blades, hinged transversely to their length at their inner ends, a sleeve and a fixed shaft, the sleeve being rotatively mounted on the fixed shaft, means for preventing axial movement of the sleeve on the shaft thereon and the blades set at an angle of incidence to their direction of rotation and hinged at their inner ends to the sleeve, and means whereby they can be oscillated to and from the axis of the sleeve to give by the reaction of the air a rotary motion of the sleeve.

9. Blade flapping apparatus for use in flying machines and for the propulsion of fluids, comprising a multiplicity of pairs of radially arranged flexible blades, hinged transversely to their length at their inner ends, a sleeve and a fixed shaft, the sleeve being rotatively mounted on the fixed shaft, means for preventing axial movement of the sleeve on the shaft thereon, and the blades being flexible set at an angle of incidence to their direction of rotation and hinged at their inner ends to the sleeve and means whereby they can be oscillated to and from the axis of the sleeve to give by the reaction of the air a rotary motion to the sleeve. 80
10. Blade flapping apparatus for use in flying machines and for the propulsion of fluids, comprising a multiplicity of pairs of radially arranged blades, hinged transversely to their length at their inner ends, a sleeve and a fixed shaft the sleeve being rotatively mounted on the fixed shaft, means for preventing axial movement of the sleeve on the shaft thereon and the blades set at an angle of incidence to their direction of rotation and hinged at their inner ends to the sleeve, and means whereby they can be oscillated to and from the axis of the sleeve while rotating in pairs moving in opposite directions simultaneously to give by reaction of the air a rotary motion of the sleeve. 85
11. Blade flapping apparatus for use in flying machines and for the propulsion of fluids, comprising a multiplicity of pairs of radially arranged blades hinged transversely to their length at their inner ends, a multiplicity of connecting rods, a rotating sleeve, a fixed shaft on which the sleeve rotates, means for preventing axial movement of the sleeve on the shaft, the axially slideable sleeve being mounted on the rotating sleeve, means provided for rotating the slideable sleeve with the rotary sleeve, the blades being hinged at their inner end to the rotary sleeve, each connecting rod pivoted at one end to a wing at some distance from its hinge and at the other end to the reciprocating sleeve. 90
12. Blade flapping apparatus for use in flying machines and for the propulsion of fluids, comprising a multiplicity of pairs of radially arranged blades, hinged transversely to their length at their inner ends, a sleeve and a fixed shaft, the sleeve being rotatively mounted on the fixed shaft, means for preventing axial movement of the sleeve on the shaft thereon and the blades set at an angle of incidence to their direction of rotation and hinged at their inner ends to the sleeve at the same distance along the sleeve, and means whereby they can be oscillated to and from the axis of the sleeve while rotating. 95
13. Blade flapping apparatus for use in flying machines and for the propulsion of fluids, comprising a multiplicity of pairs of radially arranged blades, hinged transversely to their length at their inner ends, a rotating sleeve, a fixed shaft on which the sleeve rotates, collars fixed on the shaft for preventing axial movement of the sleeve thereon, the blades being set at an angle of incidence to their direction of rotation and hinged at their inner ends to the sleeve, and means provided whereby they can be oscillated to and from the axis of the sleeve while rotating. 100
14. Blade flapping apparatus for use in flying machines and for the propulsion of fluids, comprising a multiplicity of pairs of radially arranged blades, hinged transversely to their length at their inner ends a rotary sleeve, a fixed shaft on which the sleeve rotates without reciprocating, the blades being set at an angle of incidence to their direction of rotation, and hinged at one end to the rotary sleeve, means for oscillating the blades about their hinge to and from the axis of the sleeve while rotating and for causing the ascending current of air produced by flapping and rotating of one pair of blades to engage and lift another pair of blades hinged to the same sleeve. 105
15. Blade flapping apparatus for use in flying machines and for the propulsion of fluids, comprising a multiplicity of pairs of radially arranged blades, hinged transversely to their length at their inner ends a sleeve and a fixed shaft, the sleeve being rotatively mounted on the fixed shaft, means for preventing axial movement of the sleeve on the shaft thereon, and the blades set at an angle of incidence to their direction of rotation and hinged at their inner ends to the sleeve, and means whereby they can be oscillated to and from the axis of the sleeve, to give by the reaction of the air a rotary motion to the sleeve, each member of a pair of wings being at an angle of 180° to its fellow and hinged to the sleeve at the same distance along the sleeve. 110
16. Blade flapping apparatus for use in flying machines and for the propulsion of fluids, comprising a multiplicity of pairs of radially arranged blades, hinged transversely to their length at their inner ends, a sleeve and a fixed shaft, the sleeve being rotatively mounted on the fixed shaft, means for preventing axial movement of the sleeve on the shaft thereon, and the blades set at an angle of incidence of from 5° to 15° to their direction of rotation and hinged at their inner ends to the sleeve and means whereby they can be oscillated to and from the axis of the sleeve. 115
17. Blade flapping apparatus for use in flying machines and for the propulsion of fluids, comprising a multiplicity of pairs of radially arranged blades, hinged transversely to their length at their inner ends, a multiplicity of connecting rods, a rotating sleeve, a fixed shaft on which the sleeve rotates, means for preventing axial movement of the sleeve on the shaft, the axially slideable sleeve being mounted on the rotating sleeve, a feather and keyway between the sliding and rotating sleeves, the blades being hinged at their inner end to the rotary sleeve, each connecting rod pivoted at one end to a wing at some distance from its hinge and at the other end to the reciprocating sleeve. 120
18. Blade flapping apparatus for use in flying machines and for the propulsion of fluids, comprising a multiplicity of pairs of radially arranged blades, hinged transversely to their length at their inner ends, a multiplicity of connecting rods, a rotating sleeve, a fixed shaft on which the sleeve rotates, means for preventing axial movement of the sleeve on the shaft, the axially slideable sleeve being mounted on the rotating sleeve, means provided for rotating the slideable sleeve with the rotary sleeve, a thrust bearing, on the sliding sleeve, a ring containing the thrust bearing, a second series of connecting rods, and a second axially slideable sleeve, the blades being hinged at their inner end to the rotary sleeve, each connecting rod pivoted at one end to a wing at some distance from its hinge and at the other end to the reciprocating sleeve, the ring of the thrust bearing being connected by the second series of connecting rods to the second sliding sleeve. 125
19. Blade flapping apparatus for use in flying machines and for the propulsion of fluids, comprising a multiplicity of pairs of radially arranged blades, hinged transversely to their length at their inner ends, a sleeve and a fixed shaft, the sleeve being rotatively mounted on the fixed shaft, means for preventing axial movement of the sleeve on the shaft thereon and the blades set at an angle of incidence to their direction of rotation and hinged at their inner ends to the sleeve, and means whereby they can be oscillated to and from the axis of the sleeve while rotating. 130
20. Blade flapping apparatus for use in flying machines and for the propulsion of fluids, comprising a multiplicity of pairs of radially arranged blades, hinged transversely to their length at their inner ends, a sleeve and a fixed shaft, the sleeve being rotatively mounted on the fixed shaft, means for preventing axial movement of the sleeve on the shaft thereon and the blades set at an angle of incidence to their direction of rotation and hinged at their inner ends to the sleeve, and means whereby they can be oscillated to and from the axis of the sleeve, to give by the reaction of the air a rotary motion to the sleeve, each member of a pair of wings being at an angle of 180° to its fellow and hinged to the sleeve at the same distance along the sleeve. 135
21. Blade flapping apparatus for use in flying machines and for the propulsion of fluids, comprising a multiplicity of pairs of radially arranged blades, hinged transversely to their length at their inner ends, a multiplicity of connecting rods, a rotating sleeve, a fixed shaft on which the sleeve rotates, means for preventing axial movement of the sleeve on the shaft, the axially slideable sleeve being mounted on the rotating sleeve, a feather and keyway between the sliding and rotating sleeves, the blades being hinged at their inner end to the rotary sleeve, each connecting rod pivoted at one end to a wing at some distance from its hinge and at the other end to the reciprocating sleeve. 140
22. Blade flapping apparatus for use in flying machines and for the propulsion of fluids, comprising a multiplicity of pairs of radially arranged blades, hinged transversely to their length at their inner ends, a sleeve and a fixed shaft, the sleeve being rotatively mounted on the fixed shaft, means for preventing axial movement of the sleeve on the shaft thereon and the blades set at an angle of incidence to their direction of rotation and hinged at their inner ends to the sleeve, and means whereby they can be oscillated to and from the axis of the sleeve while rotating. 145
23. Blade flapping apparatus for use in flying machines and for the propulsion of fluids, comprising a multiplicity of pairs of radially arranged blades, hinged transversely to their length at their inner ends a rotary sleeve, a fixed shaft on which the sleeve rotates without reciprocating, the blades being set at an angle of incidence to their direction of rotation, and hinged at one end to the rotary sleeve, means for oscillating the blades about their hinge to and from the axis of the sleeve while rotating and for causing the ascending current of air produced by flapping and rotating of one pair of blades to engage and lift another pair of blades hinged to the same sleeve. 150

sleeve, the second sleeve operating on the fixed shaft at a position beyond the rotating sleeve.

19. Blade flapping apparatus for use in flying machines, comprising a multiplicity of pairs of 5 radially arranged blades, hinged transversely to their length at their inner ends, a sleeve and a fixed vertical shaft, means for maintaining the vertical shaft in the vertical position, the sleeve being rotatively mounted on the fixed vertical shaft, means for preventing axial movement of the sleeve on the shaft thereon, and the blades set at an angle of incidence to their direction of rotation and hinged at their inner ends to the sleeve, and means whereby they can be oscillated to and from the axis of the sleeve to give by 10 the reaction on the air a rotary motion to the sleeve.

20. Blade flapping apparatus for use in flying machines and for the propulsion of fluids, comprising a multiplicity of pairs of radially arranged 20 blades carried on rods, and hinged transversely to their length at their inner ends, a multiplicity of connecting rods, a rotating sleeve, a fixed shaft on which the sleeve rotates, means for preventing axial movement of the sleeve on the shaft, 25 and an axially sliding sleeve, the axially slid able sleeve being mounted on the rotating sleeve,

means provided for rotating the slid able sleeve with the rotary sleeve, each alternative blade carrying rod being extended beyond its pivot, the rods carrying the blades being hinged at one end to the rotary sleeve and each connecting rod pivoted at one end to the reciprocating sleeve, and each extended blade carrying rod pivoted at the end of its extended portion to the other end of its connecting rod, while the intermediate blade carrying rods are pivoted at some distance from its hinge to the other ends of their corresponding connected rods.

21. Blade flapping apparatus for use in flying machines and for the propulsion of fluids, comprising a multiplicity of pairs of radially arranged blades, hinged transversely to their length at their inner ends, a sleeve and a fixed shaft, the sleeve being rotatively mounted on the fixed shaft, means for preventing axial movement of the sleeve on the shaft thereon means whereby the resistance of the air to the upward angular movement of each blade will cause rotation of the wings about their common axis, the blades being hinged at their inner ends to the sleeve, and means whereby they can be oscillated to and from the axis of the sleeve.
